UNITED STATES PATENT OFFICE.

JAMES P. REES, OF DES MOINES, IOWA, ASSIGNOR OF ONE-HALF TO ELMER E. ROBEY,
OF DES MOINES, IOWA.

SHIRT-FRONT ATTACHMENT.

1,098,638.

Specification of Letters Patent. Patented June 2, 1914.

Application filed June 25, 1912. Serial No. 705,872.

To all whom it may concern:

Be it known that I, JAMES P. REES, a citizen of the United States, residing at Des Moines, in the county of Polk and State of Iowa, have invented certain new and useful Improvements in Shirt-Front Attachments, of which the following is a specification.

This invention relates to devices adapted to be attached to the bosom portions of shirts to hold the same straight and prevent the bosom from wrinkling when the wearer assumes a stooping or sitting position, and has for one of its objects to provide a simply constructed device which may be readily attached and detached and transferred from one shirt to another without changing the construction of the shirt or the attachment.

Another object of the invention is to provide a device of this character which may be readily adapted without material structural change to shirts of various forms and both to open and closed fronts.

With these and other objects in view, the invention consists in certain novel features of construction as hereinafter shown and described, and then specifically pointed out in the claims, and in the drawings illustrative of the preferred embodiment of the invention: Figure 1 is a view from the inside of a portion of a shirt including the bosom with the device applied; Fig. 2 is a detached perspective view of the improved device; Fig. 3 is an enlarged transverse section on the line 3—3 of Fig. 2.

Corresponding and like parts are referred to in the following description and indicated in all the views of the drawings by the same reference characters.

The improved device comprises a sheet metal strip 10 preferably of tempered steel, and with studs 11 projecting from the ends, the studs being preferably formed by punching the material from one side to cause protuberances on the opposite side as indicated in Fig. 3. Mounted to swing upon the member 10 near each end, is a clip device, and as the clip devices are precisely alike the description of one will suffice for both. Each clip device comprises a bar or plate 12 pivoted at 13 to the member 10 and having a lateral off set at the other end, the off set portion being folded over the body of the plate at the outer end to produce spaced side members 14—15. The side member 14 is in alignment with and forms a continuation of

the bar 12, and is united at 16 to the portion 14. The portions 14—15 thus extend in parallel relations to each other and are spaced apart a distance equal to the thickness of the member 10. The portion 15 of the clip thus bears against the outer points of the spurs 11 and thus operates to hold an article firmly coupled to the member 10, as hereafter explained. Slight recesses 17 are formed in the outer end of each clip member to form a thumb grip 18 to assist in rotating the clip member upon its pivot.

The improved device is designed to be located inside the shirt bosom alongside the central plait, and with the clip members designed to be located upon opposite sides of the plait and to thus compress the material of the shirt against the protuberances 11 and hold the device firmly coupled to the shirt.

The member 10 corresponds substantially in length with the bosom of a shirt and when applied one of the clip members will be attached near the neckband and the other clip member attached to the shirt bosom near the lower end. By this simple means it will be obvious that a stay is produced which may be readily applied to the shirt front and which will hold the latter from folding together and will not wrinkle or be puffed outwardly when the wearer assumes a sitting or stooping position. By this simple means the shirt front is maintained at all times in a symmetrical form and by placing the attachment upon the inner face of the bosom, it will not be perceptible to the observer and will thus not detract from the appearance of the bosom.

The improved device is readily adaptable to all forms and styles of shirts and may be applied to open or closed fronts with equal facility.

The improved device is simple in construction, can be inexpensively manufactured and applied, and readily attached or detached or transferred from one shirt to another when required.

Having thus described the invention, what is claimed as new is:

1. A stay member, studs formed integrally therewith, and clamping devices pivoted to the stay member and coacting with said studs to hold a garment between them.

2. A stay member of resilient material having roughened portions at the ends, and

clamping devices pivoted to the stay member and coacting with the roughened portions thereof to hold a garment between them.

- 5 3. A stay member, clamping devices pivoted to the stay member near the ends and bearing over one edge of the same, and with a thumb receiving projection extending beyond the ends of the stay member.
- 10 4. A stay member having roughened portions at the ends, clamping devices pivoted at one end to the stay member and with the free end bent into U-shape transversely for engaging over the stay member at one edge
- 15 5. A stay member, clamping devices pivoted to the stay member near the ends, the free ends of said clamping devices being bent into U shape and engaging over the same 20 edge of the stay member.

6. A stay member including a single bar, studs formed adjacent each terminal of said bar by stamping the body portion, clamping devices pivoted terminally of the said bar, and a thumb projection formed integrally with said clamping devices and extending beyond the ends of the said stay member.

In testimony whereof I affix my signature in presence of two witnesses.

JAMES P. REES. [L. S.]
